UNITED STATES PATENT OFFICE.

FRANK C. MOCK, OF CHICAGO, ILLINOIS, ASSIGNOR TO STROMBERG MOTOR DEVICES COMPANY, OF CHICAGO, ILLINOIS, A CORPORATION OF ILLINOIS.

FUEL-SUPPLY SYSTEM FOR INTERNAL-COMBUSTION ENGINES.

1,315,231.

Specification of Letters Patent. Patented Sept. 9, 1919.

Application filed October 24, 1913, Serial No. 797,017. Renewed February 25, 1918. Serial No. 219,156.

To all whom it may concern:

Be it known that I, FRANK C. Mock, a citizen of the United States, residing at Chicago, in the county of Cook and State of Illinois, have invented a certain new and useful Improvement in Fuel-Supply Systems for Internal-Combustion Engines, of which the following is a full, clear, concise, and exact description, reference being had 10 to the accompanying drawings, forming a part of this specification.

My invention relates to an improved fuel supply system for internal combustion engines of the constant pressure type and it is particularly applicable to internal combustion engines in which a carburetor is employed for producing a proper vapor fuel mixture for operating the engine.

In the past, various systems have been employed for supplying fuel to carburetors for internal combustion engines, as, for example, systems in which pressure is applied to the surface of the liquid fuel in the fuel tank for the purpose of forcing the fuel through 25 the piping connecting said tank with the carburetor. Systems of this kind have been open to the serious objection that the entire fuel system must be made air-tight so as to avoid leaks, including the closures for the 30 openings used to fill the fuel tanks and, in practice, it is found very difficult to maintain such a condition. In other systems, it has been proposed to maintain a supply of liquid fuel above the level of the carburetor 35 in one way or another, so that said fuel supply will be subjected to static pressure and, therefore, be maintained at substantially constant pressure. Devices proposed heretofore for accomplishing this result have 40 been open to the objection that they are not uniform in operation and that, for many conditions, the operation of the engine is interrupted by air getting into the fuel supply pipe instead of the liquid fuel, as a result of which the engine frequently would 45 stop.

It is the particular purpose of my invention to provide an improved means for maintaining a supply of liquid fuel in a receptacle at or above the level of the carburetor so that liquid fuel will be maintained at all times in the receptacle and that the operation of the supply mechanism will be positive for all varying conditions of operation 55 of the engine.

The several drawings illustrating my invention are as follows:

Figure 1 shows diagrammatically my device connected with an engine and supply tank, the fuel receptacle and devices employed for controlling the supply of fuel thereto being shown partially in section.

Fig. 2 shows in a view similar to Fig. 1 a modified construction of fuel receptacle which is adapted for use in connection with 65 the system shown in Fig. 1.

Similar numerals refer to similar parts throughout the several views.

As shown in Fig. 1, an internal combustion engine is illustrated diagrammatically 70 at 1 and is provided with an intake manifold 2 in the supply passage 3, of which a Venturi tube 4 is formed. A carburetor 5 preferably having a float-controlled or level-controlled valve to govern the supply of 75 liquid fuel thereto is connected with the lower end of the supply passage 3 and this carburetor is connected by means of a pipe 6 with the bottom of the fuel receptacle 7. The receptacle 7 has connected with its top 80 a pipe 8 terminating in a nozzle 9 in the Venturi tube 4, so that the suction exerted by the engine will produce upon the nozzle 9 an aspirating effect, which will thereby produce a corresponding suction in the 85 pipe 8.

The receptacle 7 has located in its upper portion a smaller receiving receptacle 10, into which the liquid fuel is delivered from a pipe 11 extending to the fuel tank 12. A 90 stop cock 13 is provided in the pipe 11 so that communication between the receptacle 7 and the tank 12 may be interrupted when desired. The tank 12 is closed by means of a screw plug 14 through which an air vent 95 15 is formed.

The receiving receptacle 10 has mounted therein a siphon tube 16, the shorter leg of which terminates slightly above the bottom of the receptacle 10 and the longer leg of 100 which extends through the bottom, so as to discharge the contents of the receiving receptacle 10 into the central portion of the receptacle 7, where the fuel is held when the valve 17 is closed and from which the 105 fuel is discharged into the bottom part of the receptacle 7 when the valve 17 is opened. The siphon tube 16 is entirely contained within the receptacle 10 with the exception 110 of the projecting portion of its longer leg,

so that the siphon may be wholly covered by the liquid fuel when the fuel has reached a level near the top of the receiving receptacle tank. The central portion of the receptacle 5 above the wall 18 contains a float 19 supported by an arm 20 from a pivot 21 in an offset portion extending from the receptacle 7. The other side of the float 19 is connected by a loose joint with the lower end of the 10 valve rod 22, the upper end of which passes through a guide 23 and terminates in a valve 24 arranged to engage the valve seat formed in the end of the pipe 8 when the float 19 is raised. The lower portion of the receptacle 15 7 is connected with the receiving receptacle 10 by the pipe 25, which terminates at its upper end in an aperture of restricted cross-section substantially in the plane of the bottom of the receiving tank 10 and, at 20 its lower end, this pipe 25 projects into a cup 27 and is somewhat lower than the seat for the valve 17. The cup 27 is supported in any suitable manner from the side wall of the receptacle 7 and is provided with a small 25 aperture 28 in its bottom. An air vent 29 is connected with the lower portion of the receptacle 7, above the seat of the valve 17 and extends a sufficient height outside of the receptacle 7 so that the liquid in the tube 29 30 will not at any time flow over the top of said tube, which is open to the atmosphere.

The operation of the mechanism described is as follows:

Starting with the condition of no fuel in 35 the receptacle 7, the suction of the engine in starting will produce a partial vacuum in the pipe 8 and, as the float 19 at this time is in its lowermost position, this partial vacuum is exerted upon the pipe 11, the 40 stop cock 13 having been opened to permit the fuel to flow from tank 12 into the receptacle 7. As a result of this condition, fuel flows through the pipe 11 into the receiving receptacle 10 until it is at a sufficient level 45 to cover the siphon tube 16. During this time, the valve 17 is closed, since its open position is sufficiently close to its seat so that the suction produced in the upper portion of the receptacle 7 moves the valve to its 50 seat and holds it there. Any suitable means, as, for example, a toe 17^a may be employed for preventing the opening of the valve 17 to a position to which it will not be closed by the suction. When the siphon tube 16 55 has been covered with fuel, it is filled and at once operates to discharge the contents of the receiving receptacle 10 into the central portion of the receptacle 7, in which it is held by the closed valve 17 and, depending 60 upon the relative proportions of the central portion of the receptacle 7, the float 19 and the receiving receptacle 10, one or more discharges through the siphon 16 will be required to lift the float 19 so as to move the 65 valve 24 to a position to shut off the suction

or partial vacuum in the pipe 8 from the upper portion of the receptacle 7. The purpose of the siphon is to draw over a slug of gasolene to insure closing of the valve 24. If no means for sending a slug of liquid 70 were employed, that is if the feed to the float chamber were strictly dependent upon the suction in that chamber, a condition of equilibrium would eventually occur, where the valve 24 would be almost closed and the 75 suction would be decreased to a point where the fuel would no longer rise in the pipe 11. Enough fuel might not be drawn into the float chamber to dump through the valve 17, and there would be a dead standstill of operations, where the apparatus would be useless. The closed condition of valve 24 is maintained as long as the level of the liquid 80 above the wall 18 of the receptacle 7 is sufficient to hold the float 19 in its upper position and, during this condition, the pressure in the upper portion of the receptacle 7 is equalized by air entering the upper portion 85 of said receptacle, through the pipe 25, which action progresses somewhat slowly 90 owing to the restricted orifice at the upper end of said pipe. It is to be understood that the lower portion of the receptacle 7, below the wall 18, is maintained at all times at atmospheric pressure by means of the air 95 vent pipe 29. The air entering the upper portion of the receptacle 7 through the pipe 25 must necessarily pass through the liquid fuel remaining in the receiving receptacle 10 and the air is, therefore, carbureted to a 100 certain degree so that when such air finds its way subsequently into the manifold 2 it exercises little, if any, retarding influence upon the operation of the engine.

The bleeder 25 and the atmospheric connection 29 are employed to prevent the occurrence of a condition of equilibrium during the dumping of the gasolene through the valve 17. If the atmospheric connection and the bleeder were not employed, the 105 valve 17 might attain a position, due to the balancing of suction and the weight of the gasolene above the same, where the suction would be not great enough to draw in more gasolene and the weight of the gasolene 110 would be insufficient to dump the valve. A slow leakage might occur and the apparatus would lack positiveness of operation. The bleeder prevents such a condition of balance and causes the valve 17 to be opened. After 115 the same is opened the air from the connection 29 is drawn in, bubbles up through the descending gasolene and causes the action of dumping through the valve 17 to be rapid and positive.

When the pressure in the upper portion of the receptacle 7 has been made substantially the same as the pressure in the lower portion of said receptacle, the valve 17, which is of sufficient weight so that it will 130

not float in the liquid fuel, opens and the fuel previously contained above the wall 18 flows into the lower portion of the receptacle 7 and the cup 27 is gradually filled 5 through the small aperture 28. For this condition of the apparatus, the fuel flows through the pipe 6 to the carbureter 5, either under the influence of the head resulting from the receptacle 7 being above the 10 carbureter or from the suction of the intake manifold, or both, and in this manner the fuel is supplied to the carbureter at a substantially constant pressure. When the fuel flows from the central portion of the receptacle 15 7 to the lower portion of the receptacle, the float 19 drops and the valve 24 is again opened, which results in again establishing the partial vacuum in the upper portion of the receptacle 7, which again 20 closes the valve 17, and the operation above described is repeated, with the exception that at this time, since the cup 27 contains liquid fuel, during the equalization of the pressure after the valve 24 is closed, the 25 liquid will be drawn through the pipe 25 during the equalization operation, and little or no air will pass from the lower portion of the receptacle 7 to the upper portion of said receptacle, depending upon the capacity of the cup 27, the size of the aperture 28 in its bottom, and the height of the liquid in the lower portion of the receptacle 7. It will be understood that the valve 17 is sufficiently light so that it will close 30 readily under the influence of the suction or partial vacuum produced in the upper portion of the receptacle 7 and that, on the other hand, when the pressures in the upper and lower portions of the receptacle 7 are substantially the same, it will open readily 35 under the weight of the liquid resting upon it. It is essential that the valve 17 shall close at once when the partial vacuum is produced in the upper portion of the receptacle 7 to prevent air entering through the pipe 29, the lower portion of the receptacle 7 and through the valve 17, which action will supply air to the pipe 8 and interfere with the operation of the engine 40 45 and also fail to produce the requisite partial vacuum upon the end of the fuel pipe 11. The aperture 28 in the bottom of the cup 27 serves to retain the liquid in the cup a sufficient length of time so that it is available during the periods of equalization of pressure to wholly or in part equalize the pressures between the two portions of the receptacle 7, by flowing upward through the pipe 25 into the receiving receptacle 10. 50 55 60 65 The upper end of the pipe 6 is preferably a short distance above the bottom of the receptacle 7 so that a small amount of liquid fuel will be retained in the receptacle 7 at all times and be available for starting the engine, which may be accomplished by

means of a by-pass 30, provided with a stopcock 31 for permitting this remaining fuel to flow directly into the pipe 6 whenever the engine is started, which stopcock is closed during the running of the engine. This 70 by-pass is a precautionary device to secure a reserve supply of fuel for starting the engine in case at any time the lower portion of the receptacle should be emptied as much as the pipe 6 can do so, which condition, 75 however, will seldom occur in practice.

In the preferred construction shown in Fig. 2, the receptacle 7^a contains a supply receptacle 10^a, a siphon tube 16^a, a float 19^a pivotally supported at 21^a and a lower or 80 discharging compartment 7^b, connected with the receiving receptacle 10^a by an equalizing pipe 25^a in substantially the manner that the corresponding parts are arranged in Fig. 1. In this modified construction, the discharge compartment 7^b is provided with an air vent pipe 29^a and a discharge pipe 6^a, there being a by-pass 30^a for the same purpose as described above for corresponding parts. In this construction, however, the 90 float 19^a controls the valve 17^b so that the valve is positively opened when the float is raised. To permit this operation, it is desirable that the float may move vertically a certain distance after the valve 24^a is 95 closed by the upward motion of said float. To secure this result, the valve rod 22^a is pivotally connected at its lower end with a lever 32 pivotally supported at 33 and provided with a counterweight 34 sufficient to hold the valve 24^a in its closed condition when the float 19^a is raised. The lever 32 is extended sufficiently to the right of the pivot 33 so that the float 19^a, when in its lower position, rests upon the end of said lever 100 without, however, being connected thereto, as a result of which when the float is in its lower position, the valve 24^a is opened, since the weight of the float 19^a is sufficient to raise the counterweight 34 and, when the float 19^a is moved upward by the accumulation of liquid in the central portion of the receptacle 7^a, the valve 24^a is closed by the operation of the counterweight 34, leaving 105 the float 19^a free to continue its upward motion to a certain extent. The float 19^a is provided with an arm 35 extending to the right of its pivotal support 21^a shown in Fig. 2 and the end of this arm has passing through it the upper end of a valve rod 36 connected with the valve 17^b, the arm 35 having a certain amount of motion relatively to the valve rod determined by the collars 37 and 38. A light spring 39 is disposed between the collar 38 and the boss 110 forming the guide for the valve rod 36 so that the weight of the valve 17^b and the parts secured thereto is balanced with the valve 17^b slightly away from its valve seat. The collar 37 is preferably so disposed upon 115 120 125 130

the valve rod 36 that, when the central portion of the receptacle 7^a has little or no fuel in it and the float 19^a is in its lowermost position, the collar is engaged by the arm 35 so as to positively close the valve 17^b. As a result of the construction described, it will appear that for this modified arrangement, when the device is first operated, the valve 24^a will be open and the float 19^a will 10 be in its lowermost position, thus holding the valve 17^b in its closed position. As a result, fuel will flow into the receiving receptacle 10^a from the pipe 11^a and, in due course, the siphon tube 16^a will be covered 15 and the contents of the receiving receptacle will be discharged into the central portion of the receptacle 7^a. Depending upon the capacity of the receiving receptacle 10^a, the float 19^a and the central portion of the receptacle 7^a, one or more discharges from the receiving receptacle 10^a will be required to move the float 19^a sufficiently to permit the counterweight 34 to close the valve 24^a, and the parts are preferably so designed that the 20 particular discharge from the receiving receptacle 10^a which permits this operation is also sufficient to move the float 19^a vertically the additional amount required to bring the arm 35 into engagement with the collar. 25 and thus positively open the valve 17^b to discharge the contents of the central portion of the receptacle 7^a into the discharging chamber 7^b. While the equalizing tube 25^a is provided in this modified structure and 30 operates under certain conditions in substantially the manner shown and described above in connection with Fig. 1, for many conditions it is not required, as the float 19^a is sufficient to positively operate the valve 17^b 35 against the suction produced in the upper portion of the receptacle 7^b. For some conditions of extreme suction, however, it may be found impracticable to construct a float, 19^a, of sufficient size to positively operate the 40 valve 17^b in which case the equalizing tube 25^a is desirable to reduce the vacuum produced in the upper portion of the receptacle to assist in the opening of the valve 17^b after the valve 24^a is closed. 45 It will be understood that the liquid fuel usually employed in operating engines of this kind is gasoline or other similar liquid hydro-carbon, but my invention is equally applicable to the use of any liquid fuel, in 50 connection with which it is desired to supply the fuel to the engine directly or indirectly at constant pressure. It is to be noticed that the suction produced in the upper portion of the receptacle is dependent not 55 only upon the vacuum produced by the engine in the intake manifold, but that it also depends upon the velocity of the flow of the fuel mixture through the Venturi tube, connecting the carburetor with the intake manifold, due to the aspirator action 60 65

of the nozzle in said Venturi tube. A further and important result secured by my invention is that the operation of the siphon in the receiving receptacle causes the float to act positively upon the valve controlling the communication between the suction pipe and the upper portion of the receptacle of the device, so that said valve will be closed positively and remain closed for a definite interval so that the liquid contained in the central portion of the receptacle may be discharged into the lower part of the receptacle rapidly and completely, which produces an equally positive operation of the float in the reverse direction, thus establishing positively an open condition of the suction valve. As far as I am aware I am the first to produce this positive operation of the mechanism in connection with a device of this kind, so that a definite and considerable quantity of liquid fuel is positively delivered to the portion of the receptacle communicating with the delivery pipe by each operation of the mechanism, as a result of which the device is positive 90 and reliable in its operation in contradistinction to the unreliable operation of devices in which the opening and closing of the suction valve is rapid so that the liquid fuel is supplied to the delivery pipe slowly 95 and frequently in too small quantity. Furthermore, as far as I am aware, I am the first to produce a device of the kind described in which the valve mechanism between the upper and lower portions of the receptacle is positively operated by the float mechanism. 100

While I have shown my invention in the particular embodiments above described, I do not, however, limit myself to these particular constructions, as I may employ many equivalent constructions without departing from the spirit of my invention. 105

What I claim is:

1. In a fuel supply system for internal combustion engines, the combination of a receptacle divided into upper and lower compartments, a discharge valve for separating said compartments, a receiving receptacle in the upper portion of the upper compartment, a siphon tube disposed in the receiving receptacle with one end projecting below the bottom of said receiving receptacle, a float in the upper compartment, a suction pipe in the upper compartment, a fuel supply pipe in the upper compartment extending to the receiving receptacle, a discharge pipe extending from the lower compartment, an equalizing connection between the lower compartment and the receiving receptacle, an air-vent pipe extending from the upper portion of the lower compartment vertically toward the top of the receptacle, a fuel supply tank connected with the fuel supply pipe, an intake manifold, a carburetor 110 115 120 125 130

- reter, a Venturi tube connecting the carbureter and manifold, a nozzle in the Venturi tube connected with the suction pipe, a feed connection extending from the carbureter to said discharge pipe, a float below said receiving receptacle and a valve for said suction pipe controlled by said float.
2. In a fuel supply system for internal combustion engines, the combination of a 10 casing divided into upper and lower compartments, a receiving receptacle in the upper compartment, mechanism controlled by the filling of the receiving receptacle to discharge substantially all of its contents into the upper compartment, a fuel supply pipe extending to the upper compartment for filling the receiving receptacle, a suction pipe communicating with the upper compartment, a discharge pipe communicating with the lower compartment, devices for interrupting communication with the suction pipe controlled by the depth of liquid in the upper compartment, mechanism for transferring the liquid from the upper compartment to the lower compartment, a fuel supply tank connected with the fuel supply pipe, an intake manifold, a carbureter, a Venturi tube connecting the carbureter and manifold, a nozzle in the Venturi tube connected with the suction pipe, and a feed connection extending from the carbureter to said discharge pipe.
3. In a fuel supply system for internal combustion engines, the combination of a 15 casing divided into upper and lower compartments, a receiving receptacle in the upper compartment, mechanism controlled by the filling of the receiving receptacle to discharge substantially all of its contents into the upper compartment, a fuel supply pipe extending to the upper compartment for filling the receiving receptacle, a suction pipe communicating with the upper compartment, a discharge pipe communicating with the lower compartment, devices for interrupting communication with the suction pipe controlled by the depth of liquid in the upper compartment, mechanism for transferring the liquid from the upper compartment to the lower compartment, a fuel supply tank connected with the fuel supply pipe, an intake manifold, a carbureter, a Venturi tube connecting the carbureter and manifold, a nozzle in the Venturi tube connected with the suction pipe, and a feed connection extending from the carbureter to said discharge pipe.
4. In a fuel supply system for internal combustion engines, the combination of a 20 casing divided into upper and lower compartments, a receiving receptacle in the upper compartment, mechanism controlled by the filling of the receiving receptacle to discharge substantially all of its contents into the upper compartment, a fuel supply pipe extending to the upper compartment for filling the receiving receptacle, a suction pipe communicating with the upper compartment, a discharge pipe communicating with the lower compartment, devices for interrupting communication with the suction pipe controlled by the depth of liquid in the upper compartment, mechanism for transferring the liquid from the upper compartment to the lower compartment, a fuel supply tank connected with the fuel supply pipe, an intake manifold, a carbureter, a Venturi tube connecting the carbureter and manifold, a nozzle in the Venturi tube connected with the suction pipe, and a feed connection extending from the carbureter to said discharge pipe.
5. In a fuel supply system for internal combustion engines, the combination of a 25 casing comprising upper and lower compartments, a receiving receptacle in the upper compartment, a fuel supply pipe extending into the upper compartment for filling the receiving receptacle, a suction pipe connected with the upper compartment, a discharge pipe connected with the lower compartment, a siphon pipe in the receiving receptacle having one of its legs extending through the bottom of said receiving receptacle, a float in the upper compartment, a valve closed by the operation of the float for interrupting communication between the suction pipe and the upper compartment, a valve controlling communication between the upper and lower compartments, a fuel 30 supply tank connected with the fuel supply pipe, an intake manifold, a carbureter, a Venturi tube connecting the carbureter and manifold, a nozzle in the Venturi tube connected with the suction pipe, and a feed connection extending from the carbureter to said discharge pipe.
6. In a fuel supply system for internal combustion engines, the combination of a 35 casing comprising upper and lower compartments, a receiving receptacle in the upper compartment, a fuel supply pipe extending into the upper compartment for filling the receiving receptacle, a suction pipe connected with the upper compartment, a discharge pipe connected with the lower compartment, a siphon pipe in the receiving receptacle having one of its legs extending through the bottom of said receiving receptacle and the other of its legs terminating above the bottom of said receiving receptacle, a float in the upper compartment, a valve controlled by the float for interrupting communication between the suction pipe and the upper compartment, a valve controlling communication between the upper and lower compartments, an equalizing pipe 40 extending from the upper portion of the lower compartment to and terminating in a restricted aperture in the bottom of the re- 45

ceiving receptacle, a fuel supply tank connected with the fuel supply pipe, an intake manifold, a carbureter, a Venturi tube connecting the carbureter and manifold, a nozzle in the Venturi tube connected with the suction pipe, and a feed connection extending from the carbureter to said discharge pipe.

7. In a fuel supply system for internal combustion engines, the combination of a casing comprising upper and lower compartments, a receiving receptacle in the upper compartment, a fuel supply pipe extending into the upper compartment for filling the receiving receptacle, a suction pipe connected with the upper compartment, a discharge pipe connected with the lower compartment, a siphon pipe in the receiving receptacle having one of its legs extending through the bottom of said receiving receptacle, a float in the upper compartment, a valve controlled by the float for interrupting communication between the suction pipe and the upper compartment, a valve for controlling communication between the lower compartment and the upper compartment, an equalizing pipe extending from the lower compartment to the receiving receptacle, a fuel supply tank connected with the fuel supply pipe, an intake manifold, a carbureter, a Venturi tube connecting the carbureter and manifold, a nozzle in the Venturi tube connected with the suction pipe, and a feed connection extending from the carbureter to said discharge pipe.

8. In a fuel supply system for internal combustion engines, the combination of a casing comprising upper and lower compartments, a receiving receptacle in the upper compartment, a fuel supply pipe extending into the upper compartment for filling the receiving receptacle, a suction pipe connected with the upper compartment, a discharge pipe connected with the lower compartment, a siphon pipe in the receiving receptacle having one of its legs extending through the bottom of said receiving receptacle, a float in the upper compartment, a valve controlled by the float for interrupting communication between the suction pipe and the upper compartment, a valve for controlling communication between the lower compartment and the upper compartment, an equalizing pipe extending from the lower compartment to the receiving receptacle, said equalizing pipe terminating in a restricted aperture in the receiving receptacle, a cup in the lower compartment surrounding the lower end of said equalizing pipe, the lower end of said equalizing pipe being lower than the valve controlling communication between the upper and lower compartments, a fuel supply tank connected with the fuel supply pipe, an intake manifold, a carbureter, a Venturi tube connecting the carbureter and manifold, a

nozzle in the Venturi tube connected with the suction pipe, and a feed connection extending from the carbureter to said discharge pipe.

9. In a fuel supply system for internal combustion engines, the combination of a casing comprising upper and lower compartments, a receiving receptacle in the upper compartment, a fuel supply pipe extending into the upper compartment for filling the receiving receptacle, a suction pipe connected with the upper compartment, a discharge pipe connected with the lower compartment, a siphon pipe in the receiving receptacle having one of its legs extending through the bottom of said receiving receptacle, a float in the upper compartment, a valve controlled by the float for interrupting communication between the suction pipe and the upper compartment, a valve for controlling communication between the lower compartment and the upper compartment, an equalizing pipe extending from the lower compartment to the receiving receptacle, said equalizing pipe terminating in a restricted aperture in the receiving receptacle, a cup in the lower compartment surrounding the lower end of said equalizing pipe, the lower end of said equalizing pipe being lower than the valve controlling communication between the upper and lower compartments, an air-vent pipe extending from the lower compartment above the level of the valve controlling communication between the upper and lower compartments upward toward the top of said casing, a fuel supply tank connected with the fuel supply pipe, an intake manifold, a carbureter, a Venturi tube connecting the carbureter and manifold, a nozzle in the Venturi tube connected with the suction pipe, and a feed connection extending from the carbureter to said discharge pipe.

10. In a fuel supply system for internal combustion engines, the combination of a 110
casing comprising upper and lower compartments, a receiving receptacle in the upper compartment, a fuel supply pipe extending into the upper compartment for filling the receiving receptacle, a suction pipe 115
connected with the upper compartment, a discharge pipe connected with the lower compartment, a siphon pipe in the receiving receptacle having one of its legs extending through the bottom of said receiving receptacle, a float in the upper compartment, a valve closed by the operation of the float for interrupting communication between the suction pipe and the upper compartment, a valve controlling communication between 125
the upper and lower compartments, devices operated by the float for opening the valve controlling communication between the upper compartment and the lower compartment after the operation of the suction-con- 130

trolling valve, a fuel supply tank connected with the fuel supply pipe, an intake manifold, a carbureter, a Venturi tube connecting the carbureter and manifold, a nozzle 5 in the Venturi tube connected with the suction pipe, and a feed connection extending from the carbureter to said discharge pipe.

11. In a fuel supply system for internal combustion engines, the combination of a 10 casing comprising upper and lower compartments, a receiving receptacle in the upper compartment, a fuel supply pipe extending into the upper compartment for filling the receiving receptacle, a suction pipe 15 connected with the upper compartment, a discharge pipe connected with the lower compartment, a siphon pipe in the receiving receptacle having one of its legs extending through the bottom of said receiving receptacle, a float in the upper compartment, a valve closed by the operation of the float 20 for interrupting communication between the suction pipe and the upper compartment, a valve controlling communication between the upper and lower compartments, devices 25 operated by the float for opening the valve controlling communication between the upper compartment and the lower compartment after the operation of the suction-controlling valve, said devices serving to positively close the valve controlling communication between the upper compartment and the lower compartment when said float is in its lowermost position, a fuel supply tank 30 connected with the fuel supply pipe, an intake manifold a carbureter, a Venturi tube connecting the carbureter and manifold, a nozzle in the Venturi tube connected with the suction pipe, and a feed connection extending from the carbureter to said discharge pipe.

12. In a fuel supply system for internal combustion engines, the combination of a receptacle divided into upper and lower 45 compartments, a discharge valve for separating said compartments, a receiving receptacle in the upper portion of the upper compartment, a siphon tube disposed in the receiving receptacle with one end projecting below the bottom of said receiving receptacle, a float in the upper compartment, a suction connection in the upper compartment, a fuel supply connection in the upper compartment extending to the receiving receptacle, a discharge pipe extending from the lower compartment, an equalizing connection between the lower compartment and the receiving receptacle, an air-vent pipe extending from the upper portion of the lower 55 compartment vertically toward the top of the receptacle, and means controlled by said float for operating said discharge valve.

13. In a fuel supply system for internal combustion engines, the combination of a 60 casing divided into upper and lower com-

partments, a receiving receptacle in the upper compartment, mechanism controlled by the filling of the receiving receptacle to discharge substantially all of its contents into the upper compartment, a fuel supply pipe 70 extending to the upper compartment for filling the receiving receptacle, a suction pipe communicating with the upper compartment, a discharge pipe communicating with the lower compartment, devices for interrupting communication with the suction pipe controlled by the depth of liquid in the upper compartment, and mechanism for transferring the liquid from the upper compartment to the lower compartment. 80

14. In a fuel supply system for internal combustion engines, the combination of a casing divided into upper and lower compartments, a receiving receptacle in the upper compartment, mechanism controlled by 85 the filling of the receiving receptacle to discharge substantially all of its contents into the upper compartment, a fuel supply pipe extending to the upper compartment for filling the receiving receptacle, a suction 90 pipe communicating with the upper compartment, a discharge pipe communicating with the lower compartment, devices for interrupting communication with the suction pipe controlled by the depth of liquid in the 95 upper compartment, and mechanism for transferring the liquid from the upper compartment to the lower compartment when communication with the suction pipe is interrupted. 100

15. In a fuel supply system for internal combustion engines, the combination of a casing divided into upper and lower compartments, a receiving receptacle in the upper compartment, a siphon in the receiving 105 receptacle having one of its legs extending through the bottom of said receiving receptacle, a fuel supply pipe extending to the upper compartment for filling the receiving receptacle, a suction pipe communicating with the upper compartment, a discharge pipe communicating with the lower compartment, devices for interrupting communication with the suction pipe controlled by the depth of liquid in the upper compartment, and mechanism for transferring the liquid from the upper compartment to the lower compartment. 115

16. In a fuel supply system for internal combustion engines, the combination of a 120 casing comprising upper and lower compartments, a receiving receptacle in the upper compartment, a fuel supply pipe extending into the upper compartment for filling the receiving receptacle, a suction pipe connected with the upper compartment, a discharge pipe connected with the lower compartment, a siphon pipe in the receiving receptacle having one of its legs extending through the bottom of said receiving recept- 130

tacle, a float in the upper compartment, a valve closed by the operation of the float for interrupting communication between the suction pipe and the upper compartment, 5 and a valve controlling communication between the upper and lower compartments.

17. In a fuel supply system for internal combustion engines, the combination of a casing comprising upper and lower compartments, a receiving receptacle in the upper compartment, a fuel supply pipe extending into the upper compartment for filling the receiving receptacle, a suction pipe connected with the upper compartment, a discharge pipe connected with the lower compartment, a siphon pipe in the receiving receptacle having one of its legs extending through the bottom of said receiving receptacle and the other of its legs terminating 15 above the bottom of said receiving receptacle, a float in the upper compartment, a valve controlled by the float for interrupting communication between the suction pipe and the upper compartment, a valve controlling communication between the upper and lower compartments, an equalizing pipe extending from the upper portion of the lower compartment to and terminating in a restricted aperture in the bottom of the receiving receptacle.

18. In a fuel supply system for internal combustion engines, the combination of a casing comprising upper and lower compartments, a receiving receptacle in the upper compartment, a fuel supply pipe extending into the upper compartment for filling the receiving receptacle, a suction pipe connected with the upper compartment, a discharge pipe connected with the lower compartment, a siphon pipe in the receiving receptacle having one of its legs extending through the bottom of said receiving receptacle, a float in the upper compartment, a valve controlled by the float for interrupting communication between the suction pipe and the upper compartment, a valve for controlling communication between the lower compartment and the upper compartment, and an equalizing pipe extending from the lower compartment to the receiving receptacle.

19. In a fuel supply system for internal combustion engines, the combination of a casing comprising upper and lower compartments, a receiving receptacle in the upper compartment, a fuel supply pipe extending into the upper compartment for filling the receiving receptacle, a suction pipe connected with the upper compartment, a discharge pipe connected with the lower compartment, a siphon pipe in the receiving receptacle having one of its legs extending through the bottom of said receiving receptacle, a float in the upper compartment, a valve controlled by the float for interrupt-

ing communication between the suction pipe and the upper compartment, a valve for controlling communication between the lower compartment and the upper compartment, an equalizing pipe extending from the lower compartment to the receiving receptacle, said equalizing pipe terminating in a restricted aperture in the receiving receptacle, and a cup in the lower compartment surrounding the lower end of said equalizing pipe, the lower end of said equalizing pipe being lower than the valve controlling communication between the upper and lower compartments.

20. In a fuel supply system for internal combustion engines, the combination of a casing comprising upper and lower compartments, a receiving receptacle in the upper compartment, a fuel supply pipe extending into the upper compartment for filling the receiving receptacle, a suction pipe connected with the upper compartment, a discharge pipe connected with the lower compartment, a siphon pipe in the receiving receptacle having one of its legs extending through the bottom of said receiving receptacle, a float in the upper compartment, a valve controlled by the float for interrupting communication between the suction pipe and the upper compartment, a valve for controlling communication between the lower compartment and the upper compartment, an equalizing pipe extending from the lower compartment to the receiving receptacle, said equalizing pipe terminating in a restricted aperture in the receiving receptacle, and a cup in the lower compartment surrounding the lower end of said equalizing pipe, the lower end of said equalizing pipe being lower than the valve controlling communication between the upper and lower compartments, and an air-vent pipe extending from the lower compartment above the level of the valve controlling communication between the upper and lower compartments upward toward the top of said casing.

21. In a fuel supply system for internal combustion engines, the combination of a casing comprising upper and lower compartments, a receiving receptacle in the upper compartment, a fuel supply pipe extending into the upper compartment for filling the receiving receptacle, a suction pipe connected with the upper compartment, a discharge pipe connected with the lower compartment, a siphon pipe in the receiving receptacle having one of its legs extending through the bottom of said receiving receptacle, a float in the upper compartment, a valve closed by the operation of the float for interrupting communication between the suction pipe and the upper compartment, a valve controlling communication between the upper and lower compartments, and devices operated by the float for opening the

valve controlling communication between the upper compartment and the lower compartment after the operation of the suction-controlling valve.

5 22. In a fuel supply system for internal combustion engines, the combination of a casing comprising upper and lower compartments, a receiving receptacle in the upper compartment, a fuel supply pipe extending into the upper compartment for filling the receiving receptacle, a suction pipe connected with the upper compartment, a discharge pipe connected with the lower compartment, a siphon pipe in the receiving 10 receptacle having one of its legs extending through the bottom of said receiving receptacle, a float in the upper compartment, a valve closed by the operation of the float for interrupting communication between the 15 suction pipe and the upper compartment, a valve controlling communication between the upper and lower compartments, and devices operated by the float for opening the valve controlling communication between the 20 upper and lower compartments, after the operation of the suction-controlling valve, said devices serving to positively close the valve controlling communication between the upper compartment and the lower compartment 25 when said float is in its lowermost position.

30 23. In combination a liquid fuel supply receptacle, said receptacle having two chambers, a float in one of said chambers, a suction pipe communicating with said one chamber, a liquid receiving vessel, a fuel supply connection adapted to discharge into said vessel, means to dump the liquid from said vessel into the part of the receptacle 35 containing said float, and valve means controlled by said float for discharging said fluid to said other chamber.

40 24. In combination, an internal combustion engine, a carbureter connected with the intake of said engine, a fuel supply tank below the level of said carbureter and having atmospheric pressure admitted thereto,

45 an intermediate chamber above the level of said carbureter, said chamber comprising two communicating compartments, one of 50 said compartments having a float therein and being fed from said supply tank, said compartment having a connection from its top to said engine intake, whereby the pressure in said compartment may be reduced, a 55 valve operated by said float and controlling said connection, a connection between said two compartments, a valve controlling said last named connection, said valve adapted to be positively operated by said float and a 60 connection between the other of said compartments and said carbureter whereby the latter may be fed by gravity, said last named compartment having atmospheric pressure admitted thereto. 65

25. In combination, an internal combustion engine, a carbureter connected with the intake of said engine, a fuel supply tank below the level of said carbureter and having atmospheric pressure admitted thereto, 70 an intermediate chamber above the level of said carbureter, said chamber comprising two compartments having a valve controlled passageway therebetween, one of said compartments having a float therein positively 75 operating said valve and being fed from said supply tank, said compartment having a connection from its top to said engine intake, whereby the pressure in said compartment may be reduced, another valve operated by said float and controlling said connection, and a connection between the other of said compartments and said carbureter whereby the latter may be fed by gravity, 80 said last named compartment having atmospheric pressure admitted thereto. 85

In witness whereof, I hereunto subscribe my name this 22nd day of October, A. D., 1913.

FRANK C. MOCK.
